CLAIM

The ornamental design for a blood glucose measurement device, as shown and described.

DESCRIPTION

FIG. 1 is a bottom plan view of a blood glucose measurement device showing the new design;
FIG. 2 is a top plan view thereof;
FIG. 3 is a side elevation view thereof;
FIG. 4 is a rear, top perspective view thereof;
FIG. 5 is a rear, bottom perspective view thereof;
FIG. 6 is a front elevation view thereof;
FIG. 7 is a front, top perspective view thereof;
FIG. 8 is a front, bottom perspective view thereof; and,
FIG. 9 is an alternate front, bottom perspective view thereof showing the opposite side as compared to FIG. 8.
